CONTROL MECHANISM FOR COIN ACTUATED MACHINES

Alvin K. Norton, Portland, Oreg.

Application December 28, 1936, Serial No. 117,802

1 Claim. (Cl. 74—519)

This invention relates generally to vending machines, and particularly to a control mechanism for coin actuated machines.

The main object of this invention is to protect coin controlled vending machines against the improper operation thereof.

The second object is to increase the difficulty of producing an improper operation without adding to the original cost of the machine or to the complication of its mechanism.

I accomplish these and other objects in the manner set forth in the following specification as illustrated in the accompanying drawing, in which:

Fig. 1 is a perspective view of the principal element in the device.

Fig. 2 is a perspective view of the latch pawl.

Fig. 3 is a fragmentary vertical section through the mechanism directly connected to my improved device showing the parts with no coin or the wrong coin being used.

Fig. 4 is a view similar to Fig. 3 but showing the position of the parts when a correct coin has been used.

Fig. 5 is a vertical section taken along the line 5—5 in Fig. 3.

Similar numbers of reference refer to similar parts throughout the several views.

Before entering into an explanation of this invention, it will be understood that it relates to that class of inventions commonly known to the trade as Mills vending machines, of such class the machine described in the U. S. Patent No. 1,706,896 is an example, although the mechanism herein described does not apply to the mechanism of this particular patent.

In this class of machines a coin, such as a five cent piece, is inserted and a hand lever is operated for the purpose of delivering merchandise to a customer. A common fault of such machines resides in the fact that it is easily possible to operate these machines in a manner to make several deliveries of merchandise upon the making of one payment in money, this usually being accomplished by drilling a small hole in the case of the machine and inserting a wire by means of which the machine can be made to function improperly.

In order that the object of the present invention and its relation to existing machines may be better understood, it is stated that the coin controlled bar 10 is identical with those now in use on the machines referred to and the movability of this bar is determined by the insertion of a proper coin in a slot and the operation

of certain gaging and value determining mechanism, not shown, since they do not form a part of the present invention, it being sufficient for the present purpose to know that the bar 10 is normally in a position shown in Fig. 3, but if a proper coin is inserted, it can be manually moved to the position shown in Fig. 4.

On the frame 11 is mounted a pivot 12 which carries a bell crank lever 13 whose upper end 14 is connected by means of a link 15 to the bar 10. A spring 16 returns the bar 10 to the rest position shown in Fig. 3. The lower end 17 of the bell crank lever 13 has a laterally turned flange 18 above which is disposed the hook 19 of a manually operated lever 20.

A downward movement of the lever 20 from the position shown in Fig. 3 will cause the underside 21 of the hook 19 to engage the flange 18 and rock the lever 13 and if the proper coin has been inserted, to move the bar 10 to the position shown in Fig. 4.

Disposed on the frame 11 is a screw 22 upon which is pivotally mounted a latch pawl 23 whose hook 24 is adapted to engage a lug 25 projecting from the bar 10 when the parts are in the position shown in Fig. 4. The pawl 23 is provided with a downturned stop arm 26 adapted to engage the stop lug 27. Also formed on the pawl 23 is a trip lug 28 which extends downwardly. The pawl 23 has its hook 24 normally urged in a downward direction by means of a spring 29. A cover 30 and side wall 31 form a part of the machine casing.

Referring more particularly to my invention, same will be seen to consist of a rock lever 32 which is pivotally mounted on the screw 33 which is mounted on the frame 11. The lever 32 is urged downwardly by means of a spring 34 whose lower end is attached to the frame 11. The end 35 of the lever 32 has a downwardly extending portion 36 which has an inturned portion 37 whose underside is adapted to engage the hook 19 and whose upper side is adapted to engage the trip lug 28. One side 38 is curled upwardly to facilitate the assembling of the parts and has no other bearing on the present invention. The same is true of the downturned portion 39.

It will be understood that in the operation of machines of this type a coin is first inserted, as stated, and if it is a proper coin permits the bar 10 to be moved, or if it is an improper coin or a slug prevents the bar 10 from being moved. The lever 20 is then depressed and when the underside 21 of the hook 19 engages the flange 18

18 and moves the bell crank lever 13, an effort is made to move the bar 10. If it is permitted to move by the proper coin, it moves to the position shown in Fig. 4, that is, in a latched position. During this movement of the lever 20, certain other operations have been occurring elsewhere in the machine, among which are the selection of the number of articles to be delivered and the ejection thereof, that is, the actual 10 delivery of the articles to the purchaser.

It is the purpose of the present device to prevent a repetition of the delivering operation, that is, to limit it to one delivery operation to each selecting operation, since an attempt to repeat 15 the delivery operation involves a return or upward movement of the lever 20.

It can be seen that with my device when the lever 20 is raised to a point where the member 37 engages the trip lug 28, there is an almost 20 instantaneous release of the bar 10 which returns

to its rest position which in turn prevents any further manipulation of the machine until another coin is inserted. In other words, I have constructed my device in a manner as to eliminate the period during which the mechanism 5 can be juggled for the purpose of making incorrect deliveries.

I claim:

In a machine of the class described, a rock lever having a pivotal opening formed between 10 the ends thereof, both of said ends being turned laterally in the same direction and one of said laterally turned ends being turned downwardly and then inwardly toward the pivotal opening, said last mentioned end having a curved shoe 15 formed transversely with the body of said lever and extending upwardly on the side opposite said first mentioned inturned ends.

ALVIN K. NORTON. 20
